Cutlery,

DESIGN.

W. ROGERS.

Knife, Fork, and Spoon Handles.

Patented April 8, 1873.

No. 6,585.

B. F. Blakeslee

Jeremy W Bliff

William Rogers

UNITED STATES PATENT OFFICE.

WILLIAM ROGERS, OF HARTFORD, CONNECTICUT, ASSIGNOR TO LUCY J.
ROGERS, OF SAME PLACE.

DESIGN FOR KNIFE, FORK, AND SPOON HANDLE.

Specification forming part of Design No. **6,585**, dated April 8, 1873; application filed March 22, 1873.

To all whom it may concern:

Be it known that I, WILLIAM ROGERS, of the city and county of Hartford and State of Connecticut, have invented or discovered a new and useful Design for Knife, Fork, Spoon Handle, &c.; and to enable others skilled in the art to make the same, I will proceed to describe.

In the accompanying drawing is shown the outline, shape, or pattern of the handle. The line just inside of the outline edge of the handle is a bead configuration. Inside of this

bead configuration the enlarged portion of the handle is embellished with a second bead and quirks—the whole shape and configuration combined to produce a new and rich design for a handle.

What I claim as my invention is—

A design for a handle for knife, fork, spoon, as above shown and described.

WILLIAM ROGERS.
